UNITED STATES PATENT OFFICE.

JOHN R. BURRESS, OF TULSA, OKLAHOMA.

AUTOMATIC SWITCH-POINT-LOCKING DEVICE.

1,393,662.

Specification of Letters Patent. Patented Oct. 11, 1921.

Application filed April 20, 1920, Serial No. 375,206. Renewed March 3, 1921. Serial No. 449,499.

To all whom it may concern:

Be it known that I, JOHN R. BURRESS, a citizen of the United States, residing at Tulsa, in the county of Tulsa and State of Oklahoma, have invented certain new and useful Improvements in Automatic Switch-Point-Locking Devices; and I do hereby declare the following to be a full, clear, and exact description of the invention, such as will enable others skilled in the art to which it appertains to make and use the same.

This invention relates to new and useful improvements in automatic switch locking devices for preventing side swiping or wrecking of a train or car on a side or spur track by the passing of a train on the main track and has for its primary object the provision of means for the positive locking of the switch against accidental or manual operation until the train or car has reached a point of safety on the side or spur track, thereby obviating a trainman from closing the switch to the main track before the train or car has reached a point of safety or been positioned sufficiently far enough on said side or spur track to prevent side swiping.

Another object of this invention is the provision of an actuating member associated with the switch and the spur or side track thereof and adapted to be depressed by the train or car to positively lock the switch until the train or car has reached a point beyond the usual derailing point of said spur or side track, thereby preventing the leaving of the train or car between said derailing point and the switch and the throwing of the switch to open the main track when said car or train is so positioned. A further object of this invention is the provision of an automatic switch point locking device of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be herein-after more fully described and claimed.

For a complete understanding of my invention, reference is to be had to the fol-

lowing description and accompanying drawings, in which:

Fig. 1 is a top plan view illustrating an automatic switch point locking device constructed in accordance with my invention.

Fig. 2 is a side elevation illustrating the same.

Fig. 3 is a fragmentary side elevation illustrating the switch stand.

Fig. 4 is a fragmentary longitudinal sectional view illustrating the connection between the actuating bar of the switch points and the switch stand.

Fig. 5 is a fragmentary sectional view, illustrating a locking bar associated with said actuating bar.

Fig. 6 is a detail sectional view taken on the line 6—6 of Fig. 4.

Fig. 7 is a fragmentary perspective view illustrating the cooperating ends of the locking and actuating bars.

Fig. 8 is a detail sectional view illustrating the connection between the actuating member on the spur track and a shaft.

Fig. 9 is a sectional view taken on the line 9—9 of Fig. 2.

Referring in detail to the drawings, the character A indicates a main track while the character B indicates the side or spur track and which is connected to the main track A by a switch 1 including switch points 2 and 3 associated with a crossing frog 4. The switch points 2 and 3 are mounted for pivotal or swinging movement to open and close either the main track A or the spur or side track B. A connecting bar 5 is secured to the switch points 2 and 3 and passes under one of the rails of the main track A and has a bifurcated head 6 formed thereon which is pivoted to an arm 7, see

Fig. 4, secured to the lower end of a signal shaft or staff 8. The staff or shaft 8 is journaled in a switch stand 9 and carries at its upper end the usual signal 10. An arm 11 is secured to the staff or shaft 8 and moves over a locking plate 12 formed on the switch stand 9 and which is provided with spaced notches 13 to receive a handle 14 pivoted to the arm 11, providing a construction whereby the switch points 2 and 3 can be locked to close either the main track A or the spur or side track B. The switch stand

9 is formed on a base 15 that is secured to a pair of ties 16 of the main track A and has pivoted thereto a bell crank lever 17 which has one of its arms pivoted to a link 18. The link 18 is pivoted to the bifurcated head 6 for causing the bell crank lever to swing on its pivot by the movement of the connecting bar 5. The other arm of the bell crank lever 17 is pivoted to a rod 19 that extends along the main track A and is slidably mounted in brackets 20 and is pivoted to a bell crank lever 21. The bell crank lever 21 is pivoted to a bracket 22 supported by one of the ties and has a connecting rod 23 pivoted thereto which extends under the rails of the main track A and one of the rails of the spur or side track B. A bracket 24 is pivoted to the end of the connecting rod 23 and is secured to an ordinary derailing point 25 of the spur or side track, so that when the switch points 2 and 3 are positioned to close the main track A, the derailing point 25 will be automatically opened preventing a train or car on the side or spur track from moving onto the main track A or the open switch. The foregoing description relates to a well-known construction of railroad track and switch to which my invention is applicable.

30 An actuating member 26 adjacent the outer rail of the spur or side track D extends to points adjacent the derailing point 25 and the free end of the switch point 3 and is gradually inclined from its medial portion toward each end thereof. The actuating member 26 is pivotally connected to arms 27 which are in turn pivotally connected to brackets 28 secured to the rail C of the side or spur track B. Leaf springs 29 are secured to the tie and bear against the under face of the actuating member 26 for normally supporting the same in an elevated position and in a position so that its medial portion is disposed in a plane above the rail C of the side or spur track B and with its inclined ends D and E disposed slightly below the ball or tread portion of the rail C, so that the car wheels traveling on the rail B may also readily pass onto the actuating member 26 and gradually depress the same. A shaft 30 is journaled in brackets 31 secured to the rails of the tracks A and B and extends under the switch points 2 and 3 and is secured to one of the supporting arms 27 at one end and its other end is provided with an arm 32, to which a locking bar 33 is pivoted. The free end of the locking bar 33 is disposed over the bar 5 and rests on a block 33' formed integrally with said connecting bar 5 and which is provided with a notch 34. A shoulder 35 is formed on the locking bar 33 and is adapted to move into and out of the notch 34 according to the positions occupied by the switch points 65 2 and 3. A bracket 36 of substantially L-

shape is formed on the base 15 of the stand 9 and is provided with spaced and downwardly depending ears 37 between which slides the locking bar 33 to prevent the same from moving laterally in either direction. 70

In operation, when the handle 14 is moved to cause the switch points 2 and 3 to position themselves so that a car or train can pass from the main track A to the side or spur track B, the train or car engages the end E 75 of the actuating member 26 and gradually depresses the same against the tension of the springs 29 and said actuating member reaches its fullest depressed position when the wheels of the car or train pass over the frog 4 so as to cause the shaft 30 to be rotated and move the locking bar 33 so that the shoulder engages in the notch 34 of the block 33' locking the connecting bar against movement, holding the switch points 2 and 80 3 in their proper positions and preventing them from being moved by a trainman until after the car or train has passed beyond the end D of the actuating member and reached a point beyond the derailing point 25. 90

Pins 38 are secured to the car actuated member 26 and are provided with eyes to receive bolts 39 which are slidable through clamps 40 to provide a construction which will limit the upward movement of the car 95 actuated member and it is to be noted that the nuts 41 will permit adjustment or variation of the said movements.

While I have shown and described the preferred embodiment of my invention, it 100 will be understood that minor changes in construction, combination, and arrangement of parts may be made without departing from the spirit and scope of the invention as claimed.

Having thus described my invention, what 105 is claimed is:—

1. In combination, a railroad switch connecting main and side tracks, switch actuating means, a car actuated member pivotally mounted on the side track, tension means 110 supporting said car actuated member, a locking lever connected to the car actuated member, a shoulder formed on said locking lever, and a notched block secured to the switch actuating means and adapted to receive the 115 shoulder for preventing operation of the switch actuating means when the car actuated member is depressed.

2. In combination, a railroad switch connecting main and side tracks, switch actuating means, car derailing means in the side track and actuated by said switch actuating means, a car actuated member located between the switch and the derailing means on the side track, tension means supporting said 120 car actuated member, and locking means affected by the car actuating member to hold the switch actuating means against operation. 125

3. In combination, a railroad switch con- 13

necting main and side tracks, switch actuating means, a car actuated member associated with the side track, a locking lever connected to said car actuated member, a block on the 5 switch actuating means and having a notch therein, a shoulder formed on the free end of the locking member, a bracket carried by the switch actuating means, and spaced ears

formed on said bracket and slidably receiving the locking lever.

In testimony whereof I affix my signature 10 in presence of two witnesses.

JOHN R. BURRESS.
